Specification for Design.

Patented Aug. 29, 1916.

Application filed April 30, 1915. Serial No. 25,070. Term of patent 14 years.

To all whom it may concern:

Be it known that I, PETER T. BURTCHAELL, a citizen of the United States, residing at San Rafael, in the county of Marin and State of California, have invented a new, original, and ornamental Design for a Poison-Bottle, of which the following is a specification, reference being had to the accompanying drawing, forming part thereof.

In said drawing: Figure 1 is an elevation of one of the duplicate and opposite face

sides of the bottle. Fig. 2 is an elevation of one of the duplicate opposite plain sides which intervene the faces before referred to.

I claim:

The ornamental design for a poison bottle, as shown.
